U.S. Appl. No. 11/967,992, Carl Cetera.

Primary Examiner—Catherine R Oliver

(57)

CLAIM

The ornamental design for the pill case, as shown and described.

DESCRIPTION

FIG. 1 is a front right side perspective view of the pill case showing my new design;

FIG. 2 is a front left side perspective view thereof;

FIG. 3 is a top plan view thereof;

FIG. 4 is a front elevational view thereof;

FIG. 5 is a right side elevational view thereof;

FIG. 6 is a left side elevational view thereof;

FIG. 7 is a rear elevational view thereof;

FIG. 8 is a bottom plan view thereof;

FIG. 9 is a front right side perspective view thereof with the lid open;

FIG. 10 is a front left side perspective view thereof with the lid open;

FIG. 11 is a front left side perspective view thereof surrounded by two alternate embodiments; and,

FIG. 12 is a front right side perspective view thereof surrounded by the same two alternate embodiments illustrated in FIG. 11.

The broken lines depicting environmental structure are for illustrative purposes only and form no part of the claimed design.
